UNITED STATES PATENT OFFICE

140,098

DESIGN FOR A WRITING CASE

Ernest E. Koch, Forest Hills, N. Y.

Application June 1, 1944, Serial No. 113,827

Term of patent 3½ years

(CL. D74—1)

To all whom it may concern:

Be it known that I, Ernest E. Koch, a citizen of the United States of America and residing in Forest Hills, New York, have invented a new, original, and ornamental Design for a Writing Case, of which the following is a specification, reference being had to the accompanying drawing, forming part thereof.

Fig. 1 is a plan view of a writing case in open position showing my new design;

Fig. 2 is a front elevational view thereof in closed position; and

Fig. 3 is a plan view of the back of the case in open position and on a reduced scale.

I claim:

The ornamental design for a writing case, as shown.

ERNEST E. KOCH.
